CLAIM

The ornamental design for a bottle, as shown and described.

DESCRIPTION

FIG. 1 is a left, front, top perspective view of a bottle according to my design;

FIG. 2 is a front elevational view thereof, the back elevational view being a mirror image thereof;

FIG. 3 is a side elevational view thereof, the opposite side being a mirror image thereof;

FIG. 4 is a top plan view thereof; and,

FIG. 5 is a bottom plan view thereof.

The broken-line illustration of bottle caps are environmental only and form no part of the claimed design.

FIG. 1

FIG. 3

FIG. 4

FIG. 5
